CLAIM

The ornamental design for a light fixture system, as shown and described.

DESCRIPTION

FIG. 1 shows a top perspective view of a connector incorporated in a hard wire box of the light fixture system.

FIG. 2 shows a bottom perspective view of the design of FIG. 1; and,

FIG. 3 shows a side elevation view of the design of FIG. 1. The broken line is included for illustrative purposes only and forms no part of the claimed design
